UNITED STATES PATENT OFFICE.

HENRY JANSEN, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING CARRIER.

Application filed March 20, 1926. Serial No. 96,123.

My invention relates to braiding carriers, and my main object is to enable the use of a loaded bobbin of the maximum diameter and capacity permitted by the requisite passing of the carriers in their intersecting paths. To this end the invention provides for the avoidance of any carrier parts which project radially beyond the loaded bobbin, by fixedly mounting the latter upon a hollow axial standard of the carrier, and by employing a thread-tensioning unit which is rotatably mounted in said hollow standard and intermittently rotated therein as automatically controlled by the tensioning of the bobbin-leaving thread; as fully set forth in connection with the accompanying drawings illustrating a preferred embodiment of the invention, the novel features of which are clearly defined in the subjoined claims.

Fig. 1 is a vertical-section view showing the essential features of my invention as applied to a carrier adapted to ride vertically in the usual race-way plate of a braiding machine; the lock arm of the tensioning mechanism being illustrated as raised by the tensioning of the withdrawing thread.

Fig. 2 is a plan view thereof; in section on the line 2—2 of Fig. 1.

Fig. 3 is a separate view of the unwound bobbin, showing its non-rotary seating upon the fixed carrier standard.

Fig. 4 is a separate view of the complete thread-tensioning unit, showing the parts in normal position.

From the usual base portion 10 of the carrier rises a central tubular standard 11. Upon this rigid standard is removably but non-rotatively mounted the bobbin 12; the tubular body of which fits loosely thereon and is notched at its base 11^a so as to engage the correspondingly notched seat 11^b on the fixed standard 11, and the top of which is provided with a locking head 13 provided with pawl-engaging teeth as shown; said bobbin thus becoming a fixed part of the standard when in operating position thereon.

As indicated, thread material 12^a is wound directly upon the tubular bobbin to any amount desired within the limit fixed by the required free passing of cooperating carriers; there being no radially projecting carrier parts in my improved construction to otherwise limit the loaded diameters of the fixedly mounted bobbins.

The bobbin 12 being non-rotatively

mounted as stated, I provide for withdrawing the thread therefrom by means of a thread-tensioning mechanism which is loosely insertable in the fixed carrier standard 11^c as a separable unit, and which is 60 freely rotated in said standard in unwinding the thread from the relatively fixed bobbin as automatically determined by the tension to which the thread is subjected; the portion of said rotating mechanism which 65 first receives the leaving thread 12^b being located within the circle of a desiredly large bobbin, so that said rotatable mechanism fixes no limit to the diameter of the latter. This unitary thread-tensioning mechanism 70 comprises a tubular casing 20 which is loosely inserted in the fixed standard 11^c, with its bottom portion 21 providing a non-frictional step-bearing and an interior connection 22 for a tension spring 23, as shown; 75 said tension spring being thus located within the loosely inserted casing 20 and being provided with a thread cap 24 enclosing the spring below its thread-engaging top eye 25, and said cap having an angular cross- 80 section corresponding with that of the casing 20 so as to prevent relative rotation in the latter, all substantially as shown in prior patent to Staub No. 1,360,810 wherein said capped tension spring is merely secured 85 within the fixed carrier standard without being rotatable therein. The cylindrical portion 26 of the casing 20, rotatively fits in the upper portion of the fixed carrier standard 11^c; and an extension 20^a thereof, above 90 the latter and the headed bobbin 12 thereon, is provided with a top axially arranged thread-guide 20^b through which the thread is taken off directly to the braiding point of the machine, and with a laterally extending bracket 20^c which carries a lock arm 35 adapted to be automatically moved into and out of stopping engagement with the locking head 13 of the fixed bobbin so as to permit 95 intermittent rotary movement of the tensioning unit as required.

The lock arm 35, as shown, is pivotally secured at 36 to the casing bracket 20^c, so as to normally extend radially inward over the toothed locking head 13 of the fixed bobbin and locate its threaded-eye end 35^a substantially in the axial line of the rotatable thread-tensioning unit; and the thread 12^b as it leaves the bobbin, engages a thread guide 35^b at the hub portion of the lock 110

arm, before passing through the end eye 35^a of the latter to the top eye 25 of the tensioning means and thence through the top eye 20^b of the casing to the braiding point of the machine in which the carrier is employed.

In operation, any slack in the bobbin-leaving thread 12^b is taken up by the tensioning means 23 while the lock arm 35 is depressed thereby into engagement with the locking head 13 of the fixed bobbin; but when slack is taken up the lock arm is raised by contact of the top eye 25 so as to permit free rotation of the whole thread tensioning unit in the carrier standard; which rotation carries the outer thread-receiving end 35^b of the lock arm around the fixed bobbin to freely unwind from the latter as required. The unwinding thread 20 passes to the outer thread-guide portion 35^b of the rotatable tensioning unit, from different lengthwise portions of the fixed bobbin and from different diameters of the latter as the unwinding proceeds, but always under tension of the spring 23, whether the latter is retracted to take up slack thread, or extended to release the locked tensioning mechanism to free rotation as called for by the angling of the withdrawn thread; the 25 permitted diameter of the wound bobbin being limited only by the providing of required clearance for the material on passing bobbins of cooperating carriers.

The essential features of my invention 35 may obviously be embodied in different forms from the preferred construction specifically set forth, and in connection with accessory devices not involved in the operation thereof, without departing from the 40 scope of the claims defining the same.

What I claim is:

1. A braiding carrier comprising a base portion having a tubular standard, a bobbin non-rotatably mounted upon said fixed 45 standard and provided with a locking head,

and a combined thread take off and tensioning unit rotatable on the axis of the standard, said unit comprising a casing rotatable in said standard and having an upwardly extending portion provided with an axially arranged take-off eye and a pivoting bracket, a thread-guiding locking arm pivoted to said bracket, and an axially arranged thread tensioning device in said casing adapted to release said locking arm, the latter being normally pressed into engagement with the bobbin locking head by the tensioned thread.

2. A braiding carrier comprising a base portion having a tubular standard, a bobbin non-rotatably mounted upon said fixed standard and provided with a locking head, and a combined thread take off and tensioning unit rotatable on the axis of the standard; said unit comprising a casing rotatable in said standard and having an upwardly extending portion provided with an axially arranged take-off eye and a pivoting bracket, a locking arm pivoted to said bracket and provided with thread guide eyes at the hub and the free end thereof respectively, and an axially arranged thread tensioning device in said casing controlling said arm to lock or release the same.

3. A braiding carrier comprising a base portion having a tubular standard; a tubular bobbin non-rotatably enclosing the fixed standard and provided with a locking head; and a rotatable thread tensioning unit comprising a tubular casing rotatably mounted in said standard and carrying a thread-engaged lock arm adapted to control its rotary movement, and a thread-engaged tensioning device movable in said rotatable casing and operative upon said locking arm to engage or disengage the same.

In testimony whereof I affix my signature.

HENRY JANSSEN.
